BOTTLE CAPPING MACHINE

Anders Josef Jonsson, Linkoping, Sweden

Application October 9, 1935, Serial No. 44,157
In Sweden October 17, 1934

9 Claims. (Cl. 226—85)

The present invention has for its object to provide a bottle capping machine of small dimensions and of a simple but effective construction. It is substantially intended to be served or operated by hand and it is constructed either for mechanical or for human driving power. The former construction may also be automatized to a certain extent.

As usual the machine is provided with a capping head and a bottle supporting plate or the like movable towards and away from the said head. By means of the said plate the top of the bottle is introduced into the head in which the cap is pressed around the top of the bottle, the said capping or closing action of the head being obtained in a known manner by pressure applied to the head.

One object of the invention is to provide an adjustable motion transmission device from the capping head to the bottle supporting plate, and vice versa, by means of which the effect of the capping operation may be independent of the distance between the capping head and the supporting plate, i. e. independent of the heights of the bottles.

Another object is to connect the said motion transmission device to an operating member in such a way that the plate may be raised and the capping pressure applied to the cap and top of the bottle by actuating said operating member alone.

A further object is to arrange the machine parts in such a way that the capping pressure is applied to the bottles in a sensible manner in order to eliminate breakage of the bottles.

Still further objects will be described in the following specification.

Two embodiments of the invention are illustrated in the accompanying drawings.

Figure 1 shows one of them, partly in section, and viewed from one side, and

Figure 2 shows the other, also in side view.

Referring to both figures numeral 5 indicates the frame of the machine, 1 the capping head, 2 a block, in which the head is disposed, 3 is the bottle supporting plate and 4 indicates a pressing member embodied as a lever mounted on the block and serving to apply the necessary closing pressure to the head. The lever consists, for example, of two parallel parts, which are rigidly united with each other and located on either side of an ear 4a of the block, the said ear serving as a bearing for the pivot 4c of the lever. The capping head is of the known construction in which the cap is applied to the top of the bottle by means of an elastic ring 20, usually made of

rubber and in the capping moment compressed by a piston-like member 21, which is pressed against the ring by the lever 4 via a roller 4b mounted between the two parts of the lever.

Referring especially to the embodiment shown in Figure 1 numeral 6 indicates the driving shaft, 7 the belt pulley of the shaft, 8, 9 a toothed gear for transmitting a low speed to a cam disk shaft 10, and 10a indicates a coupling device by means of which the wheel 9 may be coupled with the 10 shaft 10. In this machine the coupling is as usual operated by means of a treadle 10c, connected with the coupling by a bar 10b, and is retained in operative position as long as the treadle is depressed. The bottle supporting plate is provided with a stem 13 movable up and down in a vertical sleeve 14, which in its turn is movable in the same direction in a guiding part of the table 15. In the lower end of the sleeve is secured a bearing 16 for a roller 17 contacting the cam disk 18. The 20 said disk, being secured to the shaft 10, serves to lift the supporting plate to the height required for introducing the top of the bottle into the head. A buffer spring 18a within the sleeve 14 imparts a certain elasticity to the supporting plate 25 and determines the pressure acting upon the bottle from below, and at the same time it compensates small variations in the heights of the bottles.

For considerable variations in the heights of 30 the bottles the block 2 and therewith also the head 1 may be set to various heights. Thus a guide 35 for the block is embodied as a rack and the block is provided with a pinion 36 meshing with the rack so that the block may be raised 35 and lowered by turning a handwheel 37 fixed to the pinion. For fixing the block after each adjustment the block is formed to a clamping sleeve which surrounds the frame column 32 and is to be fastened to the same by means of a screw 34 40 actuated manually by a key or lever 33. The lever 4 receives its working motion, i. e. its motion downwards, from the shaft 10, for example by means of a cam disk 25 via a drawbar 26. The lower end of the bar has a stirrup or the like 21 45 provided with a roller 28 contacting the cam disk. The upward motion of the bar is effected by a spring 26a. The bar is jointed to the lever by means of a die 29, turnably secured to the lever and loosely disposed on the drawbar. Above the 50 die there is a buffer spring 30, a nut 30a and a handwheel 31 screwed on to the threaded draw bar. Thus the driving transmission from the capping head to the supporting plate may be adjusted with respect to the distance between the 55

last mentioned parts and each desired fine adjustment of the pressure acting upon the cap and on the top of the bottle is obtained. The spring 30 is of importance for obtaining a 5 "smooth" or sensible closing pressure, which is required especially when capping bottles of relatively large diameters in order to prevent the "biting off" of the top of the bottle at its mouth.

The machine works in the following manner: 10 A bottle is placed on the plate 3 in the position determined by a centering member 38 and at the same time the treadle is depressed, the cam disk 18 lifts the plate 3 so that the top of the bottle is pushed into the elastic ring with the cap 15 loosely applied on the top either prior to or after the introducing of the top into the capping head. In the meantime the cam disk 25 has been turned so far that the lever 4 begins to act on the member 21, the ring 20 is compressed, the capping is accomplished and the parts then reassume their 20 initial positions. Another bottle is placed on the plate 3 without interruption of the rotation of the shaft 10, and the operation is repeated.

Instead of a one-armed lever 4, shown in Figure 1, a two armed lever may be used and the draw bar 26 may be replaced by a push rod, the spring 26a and the roller 28 being adapted to act in the opposite direction to that intended in Figure 1. If desired, the two cam disks 18 and 30 25 may each be replaced by a crank and the draw bar 26 by a chain, wire or the like, in which case, however, the spring when used for returning the transmission parts displaced during the operation must be arranged in another way than the 35 spring 26a.

As will be easily understood the embodiment described provides good possibilities as regards the adjustment according to the heights of the bottles and as regards the fine adjustment of the 40 capping pressure, besides which said pressure may be regulated to one and the same strength in all positions of the head and by a suitably dimensioned lever 4 becomes sufficient without a great load on the driving shaft.

45 To take further precautions against the risk of too hard a pressure during the capping operation the belt pulley 7 is united with the shaft 6 by means of a friction clutch. In the embodiment shown the said clutch consists of three disks 48, 50 41 and 42, of which 48 and 42 are united with the belt pulley by means of bolts, one of which, 43, is shown in Figure 1. The two disks 48, 42 are pressed against the third disk 41, which is secured to the shaft 6 by means of springs, one of 55 which is found in Figure 1 and indicated by the numeral 44. Each of these springs is guided by a bolt 44a secured in the disk 40 and set by means of nuts 45. At a certain resistance against the rotation of the shaft 6 the disk 41 begins to slide 60 between the two other disks 48 and 42.

The embodiment shown in Figure 2 is considerably simplified and it is arranged to be served and operated by hand. Also here the block 2 may be adjusted in vertical direction on the frame 5.

65 The lever 4 is depressed by means of a handle 46 via two cam disks 47 by moving the handle in the direction of the arrow 55. The cam disks are located between two ears 48 forming bearings for the cam shaft 49. For raising the supporting 70 plate 3 the tube 14 by means of the draw bar 50 is united with one end of a two-armed lever 51, mounted on a pin 52 in a projection of the block 2 between the two parallel parts of the lever 4. For the purpose of lifting the plate 3 the other 75 end of the lever is adapted to be actuated by the

handle via a cam member, for example a roller 53, rotatably mounted between the disks 47.

As in the preceding embodiment the peripheries of the cam disks 47 and the roller 53 are so arranged relatively to one another that the lever 5 51 is actuated prior to the lever 4 so that first the top of the bottle is pushed into the capping head and then the pressure is applied to the cap around the top of the bottle. In order to receive a sufficient working movement by the roller 53 10 15 the lever is curved upwards as is shown in the drawings. The connection between the rod 50 and the tube 14 may be adjusted by means of nuts 54.

When after the closing the handle is returned 15 the levers 4 and 51 reassume their initial positions, the former by the actuation of one or more resilient members, such as the elastic ring 20 when expanding, the latter by means of the weight of the members hanging by the same. 20

By its simple construction this embodiment of the machine may be manufactured in a suitable size for mounting on a table or the like.

The machine described above may be modified in many parts without departing from the spirit 25 of my invention.

Having now described my invention, what I claim as new and desire to secure by Letters Patent is:

1. In a bottle capping machine, a liftable bottle support, a capping head, capping mechanism therein, means for adjusting the capping head relative to the support so as to adapt the machine for bottles of varying heights, a driving shaft, and a yieldable transmission from said shaft to 30 said support and capping mechanism, said transmission comprising a lever for operating said capping mechanism, a reciprocatable member actuated by said shaft, a draw member between said lever and reciprocatable member, means actuated 35 by the driving shaft for lifting and lowering said bottle support, a coupling device for connecting and disconnecting the transmission portions that control the capping operation, and means for adjusting the effective length of said draw member. 40

2. In a bottle capping machine, a frame, a liftable bottle support mounted in said frame, a capping head, capping mechanism therein, a block supporting said capping head and adjustably mounted on said frame so that the capping head 50 may be adjusted relative to the bottle support so as to adapt the machine for bottles of varying heights, a driving shaft and a yieldable transmission from said shaft to said support and capping mechanism, said transmission including a lever 55 mounted in said block and controlling the operation of the capping mechanism, a member between said lever and drive shaft, and means for adjusting the effective length of said member to compensate for adjustments of said capping head. 60

3. In a bottle capping machine, a liftable bottle support, a capping head, capping mechanism therein, means for adjusting the capping head relative to the support so as to adapt the machine for bottles of varying heights, a driving shaft, 65 and a yieldable transmission from said shaft to said support and capping mechanism, said transmission comprising a lever for operating said capping mechanism, a reciprocatable member actuated by said shaft, a draw member between said lever and reciprocatable member, means actuated by the driving shaft for lifting and lowering said bottle support, a coupling device for connecting and disconnecting the transmission portions that control the capping operation, and 70 75 75

means for adjusting the effective length of said draw member, said last-named means comprising a hand-wheel adjustably mounted on said draw member, and a yieldable connection between said 5 hand-wheel and said lever.

4. In a bottle capping machine, a frame, a lift-able bottle support mounted in said frame, a capping head, capping mechanism therein, a block 10 supporting said capping head and adjustably mounted on said frame so that the capping head may be adjusted relative to the bottle support so as to adapt the machine for bottles of varying heights, manually operable means for accurately shifting the position of said block with respect 15 to said frame, a driving shaft, a yieldable transmission from said shaft to said support and capping mechanism, said transmission including a vertical draw member, and means for adjusting the effective length of said draw member to compensate for adjustments of said capping head.

5. In a bottle capping machine, a frame, a lift-able bottle support mounted in said frame, a capping head, capping mechanism therein, a block 20 supporting said capping head and adjustably mounted on said frame so that the capping head may be adjusted relative to the bottle support so as to adapt the machine for bottles of varying heights, a lever mounted in said block and controlling the operation of the capping mechanism, a control handle mounted in said block and cooperating with said lever to operate said capping mechanism, a second lever mounted in said block, a draw member from said second lever to 25 said bottle support for lifting the latter, and cams carried by said control handle for actuating said levers.

6. In a bottle capping machine, a frame, a lift-able bottle support mounted in said frame, a capping head, capping mechanism therein, a block 30 supporting said capping head and adjustably mounted on said frame so that the capping head may be adjusted relative to the bottle support so as to adapt the machine for bottles of varying heights, a lever mounted in said block and controlling the operation of the capping mechanism, a control handle mounted in said block and cooperating with said lever to operate said capping mechanism, a second lever mounted in said block, a draw member from said second lever to 35 said bottle support for lifting the latter, cams carried by said control handle for actuating said levers, and means for adjusting the effective length of said draw member.

7. In a bottle capping machine of the character described, the combination of a vertically

adjustable capping head having an elastic capping ring to be compressed about a bottle top and a plunger to compress the capping ring, a bottle support to elevate the bottle, transmission means for operating the bottle support and plunger, comprising cam means timed to elevate the support in relation to the pressure movement of the plunger to insert the top of the bottle into the ring before compression takes place in the latter, said transmission means also including an element extending from below the bottle support to a point above the capping ring, and means to adjust the effective length of said element to accommodate an adjustment in the distance between the head and support. 5

8. In a bottle capping machine of the character described, the combination of a vertically adjustable capping head having an elastic capping ring to be compressed about a bottle top and a plunger to compress the capping ring, a 10 bottle support to elevate the bottle, transmission means for operating the bottle support and plunger, comprising cam means timed to elevate the support in relation to the pressure movement of the plunger to insert the top of the bottle into 15 the ring before compression takes place in the latter, said transmission means also including an element extending from below the bottle support to a point above the capping ring, yieldable elements arranged in the transmission means between the cam means and the support and the cam means and the plunger, and means to adjust the effective length of said element to accommodate an adjustment in the distance between the head and support. 20

9. In a bottle capping machine of the character described, the combination of an adjustable capping head having an elastic capping ring to be compressed about a bottle top and a plunger to compress the capping ring, a bottle support to 25 elevate the bottle, transmission means for operating the bottle support and plunger, comprising cam means timed to elevate the support in relation to the pressure movement of the plunger to insert the top of the bottle into the ring before 30 compression takes place in the latter, said transmission means also including an element extending from below the bottle support to a point above the capping ring, means to adjust the effective length of said element to accommodate an 35 adjustment in the distance between the head and support, and a yieldable element arranged in the transmission means between the cam means and the support. 40

ANDERS JOSEF JONSSON. 55
